SLED

Jay S. Ruffner, Freeport, Ill.

Application February 8, 1938, Serial No. 189,378

15 Claims. (Cl. 280—12.11)

This invention relates to sleds and has special reference to a sled of the type adapted to be propelled by the rider, and to a propelling mechanism which may be attached to existing sleds or incorporated directly into the sled at the time of its manufacture.

While numerous attempts have been made to devise a sled of the type herein contemplated, none of these have been successful so far as I am aware. I am of the opinion that this must be attributed largely to a failure to recognize certain important facts with respect to the problem. Among the more important of these facts is the varied nature of the surface over which a sled must travel. Sometimes the surface is hard ice, while other times it is relatively soft snow. Sometimes the surface is smooth and other times very rough. The means for engaging the surface must take these factors into consideration and must be capable of establishing a positive driving contact with each of such surfaces, and the contact must be positive, that is, there must be no failure of engagement on any stroke of the operating handle. This requires not only proper engaging means but a proper distribution of the rider's weight with relation to the driving and engaging means. Another factor is the speed which may be acquired during the driving stroke. This speed must be sufficient to maintain momentum while the return stroke is being made. The means for transmitting the power from the point of application to the surface engaging means must also be such as to maintain a sustained stroke without excessive frictional loss, and must be such as to permit of coasting during a part of the sled travel without interference from the propelling mechanism. It must also be such that the driving stroke may be started at any point in the travel of the mechanism.

An object of the invention is the provision of a sled of the type described having generally improved propelling mechanism.

A further object of the invention is the provision of a sled of the type described having improved means for establishing driving engagement with the surface of the ground.

A still further object of the invention is the provision of a propelled sled wherein a carriage is reciprocated longitudinally of the sled and improved means are provided between the carriage and the ground for establishing driving connection with the ground, and wherein improved means are provided for producing relative

longitudinal movement between the carriage and the sled.

A still further object of the invention is the provision of a propelled sled having a system of lazy-tongs, and improved means for actuating the lazy-tongs to drive the sled.

Another object is the provision of a sled wherein in the power ratio between the ground-engaging means and the handle may be adjusted so as to vary the power which can be applied through unidistance to drive the sled.

Other objects and advantages will appear from the following description and the accompanying drawings, in which—

Figure 1 is a vertical section taken longitudinally through the sled;

Fig. 2 is a bottom view thereof;

Fig. 3 is a section on the line 3—3 of Figure 1;

Fig. 4 is a fragmentary side view of the track or race showing the first leg in engagement;

Fig. 5 is a view similar to Fig. 4 showing the second leg in engagement, and

Fig. 6 is a view taken on the line 6—6 of Fig. 4.

While the invention may be embodied in a wide variety of sleds, I have herein shown it as embodied in a sled of the type having metal runners adapted to be flexed for the purpose of steering the sled, one such type being marketed under the trade-mark "Flexible Flier." The sled has spaced runners 8 and 9 curved upwardly adjacent their forward ends as shown at 11, the forward ends of the runners being pivotally connected to a metal cross member 12 by means of rivets 13 and 14. The runners are also connected at rearward points by means of cross pieces 15 and 16, the cross piece 15 carrying metal brackets 17 and 18 for attachment to the runners, and the cross piece 16 having brackets 19 and 21 likewise attached to the runners, the brackets serving to space the cross pieces 15 and 16 from the runners and support the cross pieces substantially in the plane of the cross member 12 when the runners rest upon the ground.

Boards 22 are positioned on the cross pieces 15 and 16 as best shown in Fig. 2, to provide a platform, the central board extending forward as shown at 23 to which straps 24 and 25 are pivotally attached by a pin 26. A steering lever 27 extends between the straps 24 and 25 and is rigidly secured therein by a bolt 28 and a pin 29.

The forward end of the straps 24 and 25 are pivotally secured to the cross member 12 through a rivet 31 whereby when the rider pushes upon the handle portions 32 and 33 of the steering lever, the lever is rotated about the pin 26 causing 55

the forward ends of the runners 8 and 9 to be bent in one direction or another depending upon the direction of rotation of the steering lever.

Attached to the bottom of the sled formed by the elements just described is a propelling mechanism including a pair of vertically spaced U-shaped channel members 34 and 35, the channel member 34 being inverted so that its open edge faces downward and being attached to the lower side of the cross members 15 and 16 by ears 36 on opposite sides thereof. Toward the forward end of the member, the bolt 28 passes through the member and is spaced from the strap 25 by a collar 37. The channel iron member 35 is supported on the member 34 with its open edge upward, by means of bolts 38 and 39 at opposite ends of the members and spacing collars 41 and 42. The channel iron members 34 and 35 form a guideway or race for a carriage, presently to be described.

Interposed between the members of the race is a lazy-tong construction designated generally by the numeral 42, the end links 43 and 44 at one end of the tongs being pivotally supported at their ends on the bolt 38 as shown at 45, the end links 46 and 47 at the opposite end of the lazy-tong being pivotally connected at their ends to the forward end of carriage members 48 and 49 by means of a pin 51, the carriage member 48 resting on the top of the end links, and the carriage member 49 resting against the bottom thereof. The carriage members 48 and 49 are bent intermediate their ends so that the rear ends thereof rest in a vertical plane as shown at 52 and 53 and have openings for the reception of trunnions 54 and 55 of a wheel 56 of such size as to be closely received in the race formed by the U-shaped members 34 and 35. In this particular instance the wheel 56 is a roller skate wheel having an anti-friction bearings such as ball bearings 56a. The wheel is arranged to roll freely in the race in response to actuation of the lazy-tong 42.

For the purpose of actuating the lazy-tong I have provided a frame extending transversely of the sled and around the lazy-tong and the members 34 and 35, as best shown in Fig. 3, the frame having upper and lower sides 57 and 58 and end portions 59 and 61. Arms 62 and 63, pivotally connected to the upper side 57 of the frame, connect the frame to the lazy-tongs through pivotal connections 64 and 65 at the free ends of the links 43 and 44. The links have additional holes 64a and 65a for selective reception of the connections 64 and 65 so as to permit change of the effective length of the links and a consequent change in the leverage. Likewise, arms 66 and 67 connect the lower side 58 of the frame to the lazy-tongs in the same manner. It will be seen that upon movement of the frame longitudinally of the sled the lazy-tongs will be extended and collapsed. Links 68 and 69 are secured at one of their ends against opposite sides of the end portion 59 of the frame by means of a bolt 71 and extend rearwardly for attachment to a handle. Similar links 72 and 73 are secured to the opposite end 61 of the frame by a bolt 74, and likewise extend rearwardly, the links 69 and 73 being rigidly inter-connected by a brace member 75 for the purpose of preventing the frame from tilting in response to actuation of the handle.

The handle in this instance consists of a strip of steel bent into the general form of a U and having side members 76 and 77, and a top member 78. The side members are pivotally con-

nected at their lower ends to the runners as shown at 79 and 81, and the top member has half round pieces of wood attached thereto as shown at 82 to be grasped by the rider for the purpose of swinging the handle through an arc 5 about the pivot points 79 and 81. The side members 76 and 77 have spaced holes 83 for the reception of pins 84 adapted to pass through the links 68, 69, 72 and 73 for the purpose of connecting the same to the handle for reciprocation of the actuating frame. The end portions 59 and 61 of the frame likewise have spaced openings 85 for selective reception of the bolts 71 and 74. It will be seen that by shifting the pins 84 and the pins 71 and 74 the leverage between 15 the handle and the lazy-tong may be adjusted so as to adjust the ratio of movement between the carriage and the handle.

It will be seen that upon reciprocation of the handle about its pivot point the frame is reciprocated with respect to the sled causing the lazy-tong to be extended and collapsed and thereby moving the carriage longitudinally on its race through driving and return strokes.

Directing attention now more particularly to Figs. 4 to 6, inclusive, means are therein shown for establishing driving connection between the sled and the ground, that is, the surface over which the sled is to travel which may be snow, ice or the like. This consists of laterally spaced legs 86 and 87 journaled on the trunnions 54 and 55 for free rotation thereon, and in this instance are formed of a single piece of metal and connected at their free ends as shown at 88 to provide an angularly disposed surface against which is secured a foot 89 having sharpened edges 91 terminating in a centrally disposed point 92 adapted to engage the ground or other surface 93. If desired, the opposite edges 94 of the foot may be likewise sharpened so that the foot 40 may be rotated through 180° and the new sharp edges presented to the surface when the edges 92 become dulled. This foot is preferably made of hardened material such as a hardened or alloy steel. The legs 86 and 87 and attached foot 45 preferably have an overall length such that the point 92 engages the surface 93 at an angle between about 20° and 30° with respect to a vertical line through the axis of the wheel 56. Attached to the legs 86 and 87 are a second pair 50 of legs 95 and 96 rigidly secured thereto by means of bolts 97 and 98 and side brackets 99 and 101. The free ends of the legs 95 and 96 are bent outwardly at an angle to provide feet 102 and 103, each of the feet being sharpened along the edges 104 to provide a sharp surface engaging point 105. The legs 95 and 96 are somewhat longer than the legs 86 and 87, as will appear from Figs. 4 and 5, and in this instance are so disposed that a line joining the point 92 and the axis of rotation, that is, the center of the trunnions 94 and 95, will lie at an angle of about 30° with respect to a line connecting the points 105 with the axis of rotation. Under these circumstances it will be seen that when the surface over which the sled in traveling is hard, such as a surface of ice or hard snow, the legs 95 and 96 will not engage the surface and the engaging will be done by the foot 89 in the manner shown in Fig. 4. On the other hand, when the surface is relatively soft the foot 89 will tend to be forced into the surface allowing the legs to rotate into a position such as shown in Fig. 5 wherein the legs 86 and 87 have passed beyond the vertical line through the axis. Prior to this 75

time the feet 102 and 103 engage the surface to provide driving engagement at a lower point somewhat below the surface 93. It will be understood that the number of pairs of legs may be increased to three or more depending upon conditions, each succeeding pair being of greater length.

In use the sled is positioned on the ground covered with ice or snow in the position shown in Figure 1, and the rider takes a seated position on the top boards 22 with the feet against the handle portions 32 and 33, the hands grasping the handle portion 82. With the handle in the position shown in Figure 1 it is necessary for the rider to lean forward in order to grasp the same, thus throwing the center of weight forward on the sled. As the handle is drawn backward after the fashion of the so-called "Irish mail," the weight is shifted backward on the sled. At the start of this backward pull, and while the weight is shifted forward, the ground-engaging mechanism including the legs 86 and 87, the foot 89 and in some instances the legs 95 and 96 and the feet 102 and 103, engages the ground in the region of the vertical center of gravity of the sled and rider. As the handle is drawn backward and the weight of the rider shifted backward on the sled, the ground-engaging mechanism likewise moves backward with respect to the body of the sled because of the forward movement of the sled. Thus the ground-engaging mechanism is maintained largely under the weight of the sled and rider. This causes the engaging mechanism to secure and maintain a positive engagement with the ground and prevents the engagement from being disturbed by lifting movement of the sled. It will be seen that the force applied to the sled has a lateral and vertical component, the former tending to urge the sled forward and the latter tending to lift the sled. The relative proportions of these components will vary with the angle of the ground-engaging means. I have found that for best results the angle of the legs 96 and 97 should be between about 20° and 30° from the vertical at the point where the foot 89 engages the ground in the plane of the runners. This, of course, is an approximation since the angle will vary considerably with the smoothness of the ground and with the degree to which the feet enter into the ground, but these angles appear to give the best results in providing the proper proportion of thrust tending to move the sled forward, and thrust tending to lift the sled.

It will be seen that a considerable amount of the rider's weight is carried between the roller 56 and the guideways and thus taken from the runners during the driving stroke of the parts. I have therefore employed a roller having anti-friction bearings and a smooth guideway or track so that these parts will move freely with respect to each other and thus facilitate the forward movement of the sled. Attention is also directed to the fact that the power is applied to the ground-engaging means directly at the pivot point and consequently when the driving stroke is started and the foot 89, for example, enters the ground, the drive acts somewhat in the nature of a toggle tending to push the roller and trunnions through the vertical centerline against the weight of the rider. Thus, as the weight on the sled and the power required increases, the grip of the ground-engaging device also increases so that the driving means becomes more positive as required. This results from the fact that the

carriage moves largely under the center of weight of the rider, the fact that the power is applied to the point where the ground-engaging means is pivotally supported and the arrangement of the ground-engaging means as to angle and as to free travel. It will also be noted that on the return stroke, that is, the forward stroke of the handle, the feet release from the ground and are dragged forward over the ground permitting the sled to run freely.

It will be seen that driving means are employed of a nature effective to amplify the movement of the handle. This permits the rider to impart sufficient momentum to the sled during the driving stroke to continue the movement of the sled until the mechanism can be returned for the next succeeding stroke, and permits of rapid acceleration of the sled without excessively rapid movement of the handle. I have also provided means for adjusting the amount of the amplification thereby permitting the power to be applied over a shorter distance for harder pulls, as for example, when the sled is used in soft snow or upon a hill. In this instance the driving means consists of a lazy-tong mechanism positioned horizontally and secured at the forward end of the sled. It will be understood that while there is particular merit in this mechanism, other driving means may be employed to drive the carriage, which mechanism may or may not be of the type bringing about amplified movement.

I have also provided improved means for actuating the lazy-tongs from the handle, which means provides for variation and adjustment of the mechanical advantage through adjustment of the pivot points. This means also provides uniform actuation of the two sides of the lazy-tongs resulting in smooth and uniform operation.

An important phase of the invention is the construction of the ground-engaging mechanism such that a positive engagement is insured regardless of the nature of the ground surface as shown in Figs. 4 and 5. This mechanism may take a number of different specific forms, but includes successive arms of different lengths, or their equivalents, each adapted to engage the ground at a different level so as to successively provide longer legs in case the engagement of one leg gives way and the pivot point comprising the wheel trunnions tend to pass through center. In this particular instance I have shown two successive pairs of arms, but it will be understood that the number may be increased if found to be desirable under particular circumstances.

While I have thus described and illustrated a specific embodiment of the invention I am aware that numerous alterations and changes may be made within the spirit of the invention, and I do not wish to be limited except as required by the prior art and the scope of the appended claims, in which—

I claim:

1. The combination in a sled having runners, of a guideway extending longitudinally of the sled, a relatively short carriage member manually reciprocable on said guideway through a major portion of the length thereof in a driving and a return stroke, a leg depending from said carriage for free rotation to drag freely along the ground on the return stroke of the carriage and to engage and enter into the ground to establish driving connection therewith in response to

- change in angularity thereof upon movement of the carriage rearwardly in a driving stroke.
2. The combination in a sled having runners, of a guideway extending longitudinally of the sled, a carriage member manually reciproicable on said guideway in a driving and a return stroke, a leg depending from said carriage for free rotation to drag upon the ground on the return stroke of the carriage and to engage the ground to establish driving connection therewith in response to movement of the carriage rearwardly in a driving stroke, and means for engaging the ground in response to movement of said leg through a vertical position.
3. The combination in a sled having runners, of a guideway extending longitudinally of the sled, a carriage member manually reciproicable on said guideway in a driving and a return stroke, a leg depending from said carriage for free rotation to drag upon the ground on the return stroke of the carriage and to engage the ground to establish driving connection therewith in response to movement of the carriage rearwardly in a driving stroke, and a second leg movable with respect to the first mentioned leg, shaped and supported to engage the ground later than the first but prior to the time at which the first passes through a vertical position during the driving stroke.
4. The combination in a sled having runners, of a guideway extending longitudinally of the sled, a roller movable longitudinally on said guideway in a driving and a return stroke, a pair of legs carried on said roller for free rotation with respect thereto, one of said legs being of such length as to be supported in spaced relation to the ground when the other of said legs engages the ground in the horizontal plane of the sled runners and to come into engagement with the ground at about the time when the first mentioned leg passes through a vertical position.
5. The combination in a sled having a top and runners, of a guideway extending longitudinally of the sled beneath the top and between said runners, a roller in said guideway adapted to move therein, said roller having laterally extending trunnions, means operative on said trunnions for moving the roller on said guideway in a driving and a return stroke, and means carried on said trunnions at successively increasing distances therefrom adapted to successively engage the ground at successively lower planes in response to movement of the roller in a driving stroke.
6. The combination in a sled having runners, of a guideway extending longitudinally of the sled, a carriage member reciproicable on said guideway in a driving and a return stroke, legs depending from said carriage for free rotation on a horizontal axis, one of said legs being of such length as to engage the ground in the horizontal plane of the sled runners when the leg rests at an angle between about 20° and 30° with respect to the vertical, said legs being rigidly connected together, and the other leg being of a length to engage the ground later than the first but prior to the point at which the first passes through a vertical position.
7. The combination in a sled having a top for supporting a rider in a seated position, of a handle on the forward portion of the sled adapted for reciprocation by the rider with a forward and a rearward tilting movement of the body, a track beneath the top extending longitudinally of the sled, a carriage on said track reciproicable thereon from a point forward of the vertical center of weight to a point rearwardly of said center in response to reciprocation of said handle, and means carried by said carriage for engaging the ground in response to movement of the carriage rearwardly on the track and to release and drag freely over the ground in response to return movement of said carriage.
8. The combination in a sled having a top for supporting a rider in a seated position, of a handle on the forward portion of the sled adapted for reciprocation by the rider with a forward and a rearward tilting movement of the body, a guideway beneath the top extending longitudinally of the sled, a carriage on said guideway reciproicable thereon from a point forward of the vertical center of weight to a point rearwardly of said center in response to reciprocation of said handle, means carried by said carriage for engaging the ground in response to movement of the carriage rearwardly on the guideway and to release and drag freely over the ground in response to return movement of said carriage, and means for transmitting amplified movement from the handle to the carriage.
9. The combination in a sled having a top for supporting a rider in a seated position, of a handle on the forward portion of the sled adapted for reciprocation by the rider with a forward and a rearward tilting movement of the body, a guideway beneath the top extending longitudinally of the sled, a carriage on said guideway reciproicable thereon from a point forward of the vertical center of weight to a point rearwardly of said center in response to reciprocation of said handle, means carried by said carriage for engaging the ground in response to movement of the carriage rearwardly on the guideway and to release and move over the ground in response to return movement of said carriage, and lazy-tongs interposed between the handle and the carriage to transmit amplified movement to the carriage.
10. The combination in a sled having a top and runners, of a guideway comprising spaced U-shaped channels extending longitudinally of the sled below the top and between the runners, a wheel positioned between said channels and within the grooves thereof for movement longitudinally therein, said wheel having a laterally disposed shaft, manually operable means acting on said shaft for reciprocating said wheel, and ground-engaging means freely rotatable on said shaft.
11. The combination in a sled having a top and runners, of a guideway comprising spaced U-shaped channels extending longitudinally of the sled below the top and between the runners, a wheel positioned between said channels and within the grooves thereof for movement longitudinally therein, said wheel having a laterally disposed shaft, anti-friction bearings operative between the shaft and said roller, manually operable means acting on said shaft for reciprocating said wheel, and means carried on said shaft for successively engaging the ground at different depths in response to movement of said wheel in one direction.
12. The combination in a sled having a top and runners, of a guideway extending longitudinally of the sled beneath the top and between said runners, a roller in said guideway adapted to move therein, said roller having laterally extending trunnions, means operative on said trunnions

for moving the roller on said guideway in a driving and a return stroke, and means carried on said trunnions at successively increasing distances therefrom adapted to successively engage 5 the ground at successively lower planes in response to movement of the roller in a driving stroke, said means comprising an element having feet spaced circumferentially and radially from said trunnions adapted to successively 10 engage the ground at more remote points from said trunnion as said element rotates in response to longitudinal movement of said wheel.

13. The combination in a sled having a top and runners, of a guideway extending longitudinally of the sled beneath the top and between said runners, a roller in said guideway adapted to move therein, said roller having laterally extending trunnions, means operative on said trunnions for moving the roller on said 20 guideway in a driving and a return stroke, means carried on said trunnions at successively increasing distances therefrom adapted to successively engage the ground at successively lower planes in response to movement of the roller in a driving 25 stroke, and means for moving said wheel in response to reciprocation of said handle comprising horizontally disposed lazy-tongs connected at one end to said trunnions and secured against longitudinal movement at its opposite ends, 30 and means for extending and retracting said lazy-tongs in response to reciprocation of the handle.

14. The combination in a sled having a top and runners, of a guideway extending longitudinally of the sled beneath the top and between said runners, a roller in said guideway adapted to move therein, said roller having laterally extending trunnions, means operative on said 35 trunnions for moving the roller on said

guideway in a driving and a return stroke, means carried on said trunnions at successively increasing distances therefrom adapted to successively engage the ground at successively lower planes in response to movement of the roller in a driving stroke, and means for moving said wheel in response to reciprocation of said handle comprising horizontally disposed lazy-tongs, a frame extending around said lazy-tongs adjacent the forward end of the sled, rods extending from the top and bottom of said frame to the outer extremities of two links of said lazy-tongs, and means extending between the sides of said frame and said handle for reciprocating said frame. 10

15. The combination in a sled having a top and runners, of a guideway extending longitudinally of the sled beneath the top and between said runners, a roller in said guideway adapted to move therein, said roller having laterally extending trunnions, means operative on said trunnions for moving the roller on said guideway in a driving and a return stroke, means carried on said trunnions at successively increasing distances therefrom adapted to successively engage the ground at successively lower planes 20 in response to movement of the roller in a driving stroke, means for moving said wheel in response to reciprocation of said handle comprising horizontally disposed lazy-tongs, a frame extending around said lazy-tongs adjacent the forward end of the sled, rods extending from the top and bottom of said frame to the outer extremities of two links of said lazy-tongs, means extending between the sides of said frame and said handle for reciprocating said frame, and 25 means for changing the position of said last mentioned means to change the travel of said wheel at each stroke of the handle. 30

JAY S. RUFFNER.
